Primary Examiner — Martie K Holtje(57) **CLAIM**

The ornamental design for a joined-wing, tilt-wing aircraft, as shown and described.

DESCRIPTION

FIG. 1 is a perspective front view of a joined-wing, tilt-wing aircraft;

FIG. 2 is a front elevation view of the joined-wing, tilt-wing aircraft;

FIG. 3 is a rear elevation view of the joined-wing, tilt-wing aircraft;

FIG. 4 is a left side elevation view of the joined-wing, tilt-wing aircraft; the right side view being a mirror image thereof;

FIG. 5 is a top plan view of the joined-wing, tilt-wing aircraft; and,

FIG. 6 is a bottom plan view of the joined-wing, tilt-wing aircraft.
